Primary Examiner — David Muller*Assistant Examiner* — Nathan Johnston(74) *Attorney, Agent, or Firm* — Robert C. Montgomery; Montgomery Patent & Design**CLAIM**

The ornamental design for a squeezer for a frangible container, as shown and described.

DESCRIPTION

FIG. 1 is a perspective front view of the squeezer for a frangible container, showing my new design;

FIG. 2 is a front elevation view thereof;

FIG. 3 is a rear elevation view thereof;

FIG. 4 is a right side elevation view; the left side elevation view being a mirror image thereof;

FIG. 5 is a top plan view thereof; and,

FIG. 6 is a bottom plan view thereof.

1 Claim, 5 Drawing Sheets(56)
